Term of patent 14 years

Int. Cl. D9—04

U.S. Cl. D9—175

FIG. 1 is an elevational view of a container for liquids, showing our new design, the other sides except for the side seen in FIG. 2 being substantially the same in appearance;

FIG. 2 is an elevational view looking from the right of FIG. 1;

FIG. 3 is a top plan view;

FIG. 4 is a bottom plan view; and

FIG. 5 is a sectional view taken on the line 5—5 of FIG. 1.

The dominant features of our design reside in the portions shown in full lines.

We claim:

The ornamental design for a container for liquids, as shown and described.
